Wood Industries, Inc., Detroit, Mich., a corpora-
tion of Michigan

Application December 8, 1938, Serial No. 308,304

4 Claims. (CL. 60—52)

The present invention relates to motor vehicles and particularly relates to hoisting mechanism for tilting a tiltable truck body about the chassis of a truck. Hoisting mechanisms of the type to which the present invention is directed include an hydraulic cylinder, which is pivotally connected to the chassis of the truck, having a reciprocating piston associated therewith which is connected to the truck body.

One of the primary objects of the present invention is to provide improved hydraulic hoisting mechanisms of the type mentioned wherein an hydraulic hoisting cylinder is pivotally connected to the truck chassis and is constructed in such a way that the forces of the body load exerted on the pivotal connection through the cylinder are translated thereto through a rugged and simple construction in an improved manner.

Another object of the invention is the provision of an improved hydraulic hoisting mechanism including fluid reservoir means of a novel and simple construction and arrangement.

Another object of the invention is to provide improved hydraulic hoisting mechanism whereby the weight of the structure is considerably reduced and whereby the structure is simpler and more economical to produce than prior constructions.

Another object of the invention is to provide improved hydraulic hoisting mechanisms of the type mentioned, being so constructed that pump means may be mounted on either side of the cylinder so that such mechanism may be used with different makes of trucks without alteration thereto.

Other objects of the invention will become apparent from the following specification, the drawings relating thereto, and from the claims hereinafter set forth.

In the drawings, in which like numerals are used to designate like parts in the several views throughout:

Figure 1 is a side elevational view, with parts broken away, illustrating an automotive truck having a tiltable dump body mounted thereon and including an hydraulic hoisting mechanism constructed in accordance with the present invention;

Fig. 2 is an enlarged cross-sectional view taken substantially along the line 2—2 of Fig. 1;

Fig. 3 is a cross-sectional view taken substantially along the line 3—3 of Fig. 2;

Fig. 4 is an end elevational and cross-sectional

view taken substantially along the line 4—4 of Fig. 2;

Fig. 5 is a view similar to Fig. 2, illustrating another form of the present invention; and

Fig. 6 is a cross-sectional view taken substantially along the line 6—6 of Fig. 5.

Referring to the drawings, and referring particularly to Figs. 1 through 4 thereof, one embodiment of the present invention is illustrated in which a conventional dump truck is shown at 16, having a chassis 12 and a body 14 tiltably mounted thereon for pivotal movement about transversely aligned pivots 16. The chassis 12 is provided with longitudinally extending sill members 18; and the body 14 is provided with longitudinally extending body members 19, which are adapted to rest upon the upper portions of sills 18 when the body is in its lowermost position.

In order to raise and lower the body 14 about the pivot 16, an hydraulic hoisting device, generally indicated at 20, is provided. Such hoisting device 20 comprises a cylinder 22 having one end thereof closed by an end plate 24 and the opposite end thereof closed by an end cap 26.

The cylinder 22 includes a ring-shaped member 23, of greater thickness than the thickness of the major portion of the cylinder 22 secured to one end thereof. Such member 23 is formed with an annular internal shoulder 25 and telescopically receives therein the rear end of the cylinder. The end cap 26 is removably fixed to the member 23 by means of suitable bolts. The member 23 is also provided with a tapped and tapered opening which receives a threaded plug 29 for closing the same. The cylinder may thus be filled with the actuating fluid through such opening, or such opening may be used to drain the fluid from the cylinder.

A piston 28 is slidably mounted for reciprocation within the cylinder and has a piston rod 30 coaxially fixed thereto which projects through a coaxial opening in the end cap 26. A packing means 32 may be suitably mounted on the end cap in embracing relationship to the piston rod 30 so as to prevent leakage through the cap opening as the piston rod reciprocates with respect thereto.

The rear end of the piston rod 30 projects beyond the cap 26 and is of reduced diameter, as indicated at 34. The portion 34 is adapted to be removably fixed to an angle plate having a top surface portion 36 and a downwardly extending portion 38 at an angle thereto. The reduced portion 34 may extend through a suitable aper-

ture in the portion 38 so that it lies against the underside of portion 36 and projects therealong and so that the adjacent enlarged portion abuts against the forward surface of portion 38. A U-shaped member 40 is disposed under portion 36 with the free edges bearing against the under surface of portion 36 and welded thereto. The U-shaped member 40 thus provides a mounting tunnel for the reduced end portion 34, which projects forwardly beyond the rear edge of plate 36. A nut 42 is threaded on the projecting end portion and bears against an interposed washer 44 for removably mounting the piston rod with respect to the plate member 36.

The hoisting mechanism 20 also includes oppositely disposed side wing members 46, which are formed of sheet metal and are folded along one edge thereof, with the upper and bottom walls thereof spaced from each other to provide a chamber therebetween. The members 46 are generally triangular in shape, as best shown in Fig. 2, and the inner edges 48 thereof are adapted to abut against and extend longitudinally of the cylinder 22 at diametrically opposed points. The members 46 are so positioned that the apices are disposed adjacent the rear ends of the cylinder with the base ends thereof disposed adjacent the base of the cylinder. The abutting edges of the members 46 are then welded to the cylinder 22, as indicated at 50. The forward or base ends of the members 46 are closed by end plates which are complementary in shape to the shape of the open ends of the members 46, so that such members, together with the end plates, form enclosed chambers.

The chambers formed within the wing members 46 form fluid reservoirs, which communicate with the interior of cylinder 22 through openings 52, formed in the cylinder wall adjacent the cap end of the cylinder.

In order to pivotally mount the hoisting means 20 with respect to the chassis, stub pivot shafts 54 are adapted to project through openings in the outside corners of wing members 46 adjacent the base end of the cylinder. The stub shafts 54 may be welded to the members 46 so that the reservoir chambers are sealed and so as to provide a secure mounting. The ends of the stub shafts 54 are adapted to be received within bearings 56, which are fixed to the sills 18 of the chassis at transversely aligned points.

In order that the hoisting mechanism of the present invention may be applied to any of the various makes of trucks, a pump mounting means is provided on each of the wings, so that the pump may be mounted on that wing located at the same side as the side of the engine take-off on the truck. A reinforcing plate member 58 is fixed to the under side of each of the wings 46 adjacent the base end thereof; and a reinforcing bracket plate 60 is also fixed to the top of each of the wings 46 in overlying relation to the members 58.

A gear pump 62 of conventional construction is illustrated as being mounted on one of the sides, and such mounting is effected by a plurality of bolts 64, which pass through plate member 60, the top and bottom walls of members 46, bracing plate 58, and are threaded in tapped openings in the top of pump 62 for mounting the pump 62 to the under side of wings 46. Spacers in the form of tubular sleeves 66 embrace the bolts 64, so as to brace the same and limit the tightness with which the pump 62 is drawn against the under side of the wings 46 to which it is attached.

The wings 46 are adapted to communicate with

the pump 62 through an opening 68 formed through the bottom wall of member 46 and through an aligned opening in reinforcing plates 58.

The reservoir chamber provided by that wing 46 on the side of the cylinder to which the pump is not attached has the communicating passage 68 closed by means of a closure plate 70, which is fixed to the bolts 64 by means of nuts 72.

For filling or draining the reservoir chambers provided by wings 46, tapped and tapered openings 74 are provided through the top plate 60, and aligned openings in the upper wall of wings 46. Such openings are closed by a threaded plug 76.

The gear pump 62 is adapted to be driven by means of a flexible drive shaft 78, which is connected to the take-off on the vehicle transmission in the usual way. The operation of the pump may be controlled from the driver's cab by means of an operating lever 80, which is connected to a control lever 82 mounted on the pump 62. The control lever 82 is in turn connected to a valve operating lever 84, which controls the flow of fluid through the circuit. The pump communicates with the interior of the cylinder 22 on the forward side of piston 28 through a U-shaped connection 86. Such connecting conduit 86 is placed in such communication by means of fittings 88, which are fixed to the end plate 24 and communicate through an opening 90 in the end plate.

It will thus be seen that the reciprocation of the piston 28 is effected by the circulation of the hydraulic fluid within cylinder 22 and that wing 46 to which the pump is attached. The other wing merely forms a storage reservoir and the fluid does not circulate therethrough during the operation of the mechanism. Actuation of the pump forces fluid under pressure through the conduit 86 against the forward side of piston 28, thus causing the piston to move toward the cap end. The fluid within the cylinder 22 is thereby caused to move through one of the openings 52 into the adjacent reservoir and passes therefrom through passage 68 back into the pump. By reversal of the valve lever 84, the body may be lowered, and the fluid would flow in the opposite direction.

The piston rod may be connected to the dump body 14 either directly or through suitable connecting means. In the embodiment illustrated, the piston is shown as being connected to the dump body through a linkage mechanism. Suitable pivot rods 92 are welded to the inside corner of plate member 36, as shown in Fig. 3, and such pivot shafts extend slightly beyond the ends of plate member 36.

Similar linkage members are provided at the outside ends of each of the pivot shafts 92 for connection to the body. Each of such linkage mechanisms includes a lever member 94 pivotally connected to the chassis at 96, and pivotally connected to the projecting end of pivot shaft 92 intermediate the ends thereof. Other linkage members 98 have the lower ends thereof pivotally connected to the lower end of lever 94 at 99, and have the upper ends thereof pivotally connected to the longitudinal body members 19, as indicated at 101. The linkage connection just mentioned forms no part of the present invention per se, but is merely illustrative of one manner in which the hydraulic hoisting means may be connected to the body.

From the above description, it will be evident that as the body is being raised or lowered, there

is considerable stress placed upon the pivotal connections 54. The wing members 46 not only provide a simplified and inexpensive construction for forming reservoirs, but they also serve to 5 stiffen and strengthen the construction, so that the load on the pivots 54 is more properly distributed, than in prior constructions.

Referring to Figs. 5 and 6, another embodiment of the present invention is illustrated in which the side wings forming the reservoirs and reinforcing members are of a different construction. In this embodiment of the invention, side wings 104, which correspond to the side wings 46 of the embodiment above described, are provided. 10 Each of such side wings 104 is formed of upper and lower, complementary sheet metal stampings 106 and 108, which are resistance butt welded together. In plan, the side wings 104 are generally triangular in shape and have a base end 110, which is welded to the base end of the cylinder 22. Communicating conduit portions 112 converge toward the cap end of the cylinder 22 and the ends thereof are welded to the cylinder 22 adjacent the cap end in overlying relation 15 to the communicating openings 52. The pivot shafts 54 are welded to the wings 104 at transversely aligned points for pivotal connection to the chassis. Pump mounting means similar to those described above are also provided on the 20 base ends of each of the side wings 104, as indicated at 60 and 64. The operation of this structure is the same as that described above, and the forces on the pivot 54 are distributed thereto in the same manner.

It will be appreciated that in both of the embodiments above described the side wings have dual functions. The wings act as fluid reservoirs and also provide a simplified construction in which the compression reaction carrying through 25 the cylinder from its pivots to the body load is taken by the rigid side wings in a simplified way. Considerable saving in weight is effected over prior constructions employing the ordinary cross-member abutting the end of the cylinder.

Formal changes may be made in the specific embodiment of the invention described without departing from the spirit and substance of the invention, the scope of which is commensurate 30 with the appended claims.

What is claimed is:

1. In a truck body hoisting mechanism, an hydraulic cylinder having a base end and a cap end, a piston and piston rod reciprocably mounted therein with said rod extending through said cap end, side members generally triangular in shape extending longitudinally of said cylinder and fixed to the outside thereof forming reservoir 35 chambers, the bases of said side members being

disposed adjacent the base end of said cylinder with the apex of said side members disposed adjacent said cap end, means communicating said chambers with the interior of said cylinder, and aligned pivotal mounting means connected to 5 said side members adjacent the base end of said cylinder.

2. In a truck body hoisting mechanism, an hydraulic cylinder having a base end and a cap end, a piston and piston rod reciprocably mounted 10 therein with said rod extending through said cap end, side members generally triangular in shape extending longitudinally of said cylinder and fixed to the outside thereof forming reservoir chambers, said side members being disposed with the bases thereof adjacent the base of said cylinder, means communicating said chambers with the interior of said cylinder, pivotal mounting means fixed to said side members adjacent the bases thereof, and pump mounting means fixed 15 to said side members on both sides of said cylinder.

3. In a truck body hoisting mechanism, an hydraulic cylinder having a base end and a cap end, a piston and piston rod reciprocably mounted 20 therein with the rod extending through said cap end, side members disposed at diametrically opposed positions with respect to said cylinder and extending longitudinally thereof forming reservoir 25 chambers, each of said side members being generally triangular in shape and having spaced walls, said side members being disposed with the bases thereof adjacent the base of said cylinder and with the apex thereof disposed adjacent the 30 cap end of said cylinder, those edges of said side members adjacent said cylinder extending longitudinally thereof and being welded to said cylinder, means communicating said chambers with the interior of said cylinder, and aligned pivotal 35 mounting means fixed to said side members adjacent the base end of said cylinder.

4. In a truck body hoisting mechanism, an hydraulic cylinder having a base end and a cap end, a piston and piston rod reciprocably mounted 40 therein with said piston rod extending through said cylinder, side members extending longitudinally of said cylinder at diametrically opposed portions thereof and fixed to the outside thereof, forming reservoir chambers, means communicating 45 said chambers with the interior of said cylinder, each of said side members comprising a pair of complementary stamped sections welded together and being generally triangular in shape, said side members being welded to said cylinder adjacent the base end thereof and adjacent the 50 cap end thereof, and pivotal mounting means fixedly connected to said side members.

EDWARD R. BARRETT.
